UNITED STATES PATENT OFFICE.

MASON H. CRITTENDEN, OF MINNEAPOLIS, MINNESOTA, ASSIGNOR TO
THE CRITTENDEN ROOFING AND MANUFACTURING COMPANY, OF
SAME PLACE.

MEANS FOR CLOSING LIGHT-WELLS.

SPECIFICATION forming part of Letters Patent No. 616,902, dated January 3, 1899.

Application filed August 20, 1897. Serial No. 648,869. (No model.)

To all whom it may concern:

Be it known that I, MASON H. CRITTENDEN, a citizen of the United States, residing at Minneapolis, in the county of Hennepin and State 5 of Minnesota, have invented certain new and useful Improvements in Means for Closing Light-Wells or other Openings; and I do hereby declare the following to be a full, clear, and exact description of the invention, such as 10 will enable others skilled in the art to which it appertains to make and use the same.

My invention has for its object to provide a convenient and reliable means for closing light-well or other openings in buildings, so 15 as to afford a complete separation between the different stories of the building in case of fire.

In large buildings used for mercantile purposes light-wells are usually provided which 20 extend through the different stories to the roof. If a fire occurs on any floor, these light-well openings afford a ready passage for the flames and moving currents of air and gases to the other stories or floors, thereby facilitating the spread of the fire under a strong 25 draft to all parts of the building.

The object of my invention is to provide movable ceilings adapted to close the light-well openings in the fixed ceilings whenever 30 so desired, so as to be able to confine a fire to the single story or floor where started, and they also serve to prevent the water from being poured through onto the lower floors when the fire is in an upper story. These 35 movable ceilings are provided with operating connections which are preferably so arranged as to be operative from a common source. Hence all the light-well openings may be simultaneously and quickly closed whenever 40 occasion demands.

To the ends above noted my invention consists of the novel devices and combinations of devices hereinafter described, and defined in the claims.

45 The invention in the form which it would take for closing light-well openings of considerable size is illustrated in the accompanying drawings, wherein like notations refer to like parts throughout the several views.

Figure 1 is a sectional elevation through a part of a building equipped with my invention. Fig. 2 is a detail in sectional elevation showing the sets or sections of the movable ceilings as the same would appear when in position to close the light-well opening, with some parts broken away. Fig. 3 is a similar view showing the lap-sections of a single set of the ceiling-sections as they would appear when in their idle position at one side of the light-well. Fig. 4 is a plan view with the parts in the same position as shown in Fig. 1, some portions being broken away; and Fig. 5 is a vertical section through the floor and ceiling on the line $x^5 x^6$ of Fig. 4.

Referring especially to Fig. 1, the numerals 1 2 3 represent different floors of a building, numbered upward from the ground floor. a represents one of the side or end walls, and b represents supporting-columns. c represents the fixed ceilings in the different stories. The ceilings and floors are cut away to afford the usual light-well opening d . The parts so far noted are all of the ordinary or any suitable construction common in mercantile buildings.

75 Directing attention now to my invention, I provide ceiling-sections $f f'$, which for light-well openings of large size are arranged in sets of lap or telescoping sections at the opposite sides or ends of the light-well. In the instance illustrated the sets at each side are made up of two sections $f f'$, which are arranged to lap or slide one under the other for permitting the same to assume a compact form, requiring small space when in their idle 85 position, as shown in Fig. 3. The ceiling-sections $f f'$ are made of suitable fireproof material, preferably sheet metal, reinforced by proper metallic framing and braces. The said sections $f f'$ are provided with flanged 90 wheels f^2 , which travel on angle-iron rails f^3 , made fast in any suitable way to the columns b or other parts of the fixed structure in proper position for supporting the movable ceilings, as required. The ceiling-sections $f f'$ are also provided with lateral flanges f^4 , which underreach the horizontal parts of the angle-iron rails f^3 , and thereby prevent an

opening between the movable ceiling-sections and the rails on which they are mounted to travel.

By reference to Figs. 1, 2, and 3 it may be noted that in order to permit the lap-sections $f f'$ to slide one under the other the bodies of the sections are reversely supported in respect to the trucks. The body of the forward section f' depends from the trucks, while the body of the rearward section is supported above the truck-axles. This permits the bodies of the two coöperating lap-sections $f f'$ to move one under the other with a comparatively tight joint. The rearward section f is shown as provided with a small roller f^5 , which travels on the central cross-beam f^6 of the outer or forward section f' . The rearward section f is shown as provided with a downwardly-projecting finger or bracket-iron f^7 , adapted to engage with the back main beam of the forward section f' when the latter is pulled out to its limit, and thereby cause the two sections $f f'$ to move together in their further outward travel. The diagonal braces f^8 are of less depth than the main beams f^9 of the ceiling-sections $f f'$, which construction affords the necessary clearance to permit the outer section f' to move in respect to the rearward section f without interference from the finger f^7 until the point desired is reached. The sheet-metal portions of the said sections $f f'$ are further reinforced by suitable trusses f^{10} , properly applied to the main framing of the said sections.

A pair of endless chains h are mounted on sprockets h' , carried by shafts h^2 , located at the opposite sides of the building or other convenient point beyond the opposite ends of the light-well and the limits of the ceiling-sections travel. The said chains h are mounted to travel above and below the ceiling-sections. The outer or forward section of one set—to wit, the left-hand set, as shown, of the lap-sections $f f'$ —is connected by bracket-irons h^3 or otherwise to the upper-running folds of the chains h , and the outer or forward section of the opposite or right-hand set of said lap-sections $f f'$ is connected by corresponding brackets h^4 to the under-running folds of said chains h . Hence a continuous movement of the said chains h in one direction will move the opposite sets of said lap-sections $f f'$ toward or from each other, as desired, according to the direction in which the chains h are run. The several chain-shafts h^2 , at at least one end of the chains, are in position to be operated from a common vertical shaft g by means of beveled gears g' . This vertical shaft g extends to the ground floor or other desired point and is provided with suitable means for operating the same, which means, as shown, comprise a hand-crank shaft g^2 and beveled gears g^3 . As shown, the vertical shaft g and the hand-crank shaft g^2 have their bearings in a common support g^4 , shown as resting on the ground floor 1. With this arrangement of

the operating connections it is obvious that all of the movable ceiling-sections may be simultaneously operated from the common source or hand-crank g^2 .

Normally while the building is in use during business hours the ceiling-sections will occupy their idle position to one side of the light-well opening, as shown in Fig. 3. When it is desired to close the light-well opening, the hand-crank g^2 will be turned by an operator in the proper direction. Under the initial movement of the chains h the forward sections f' will be first moved toward each other, while the rearward sections f remain stationary. Then the two sections $f f'$ will be made to move together by the engagement of the fingers f^7 with the rear main beams f^9 of the sections f' , and under the continued movement of the chains in the same direction the two sets of the ceiling-sections $f f'$ will be brought into the position shown in Fig. 2, thereby completely closing the light-well opening. By reference to Figs. 1 and 2 it will be seen that the opposing edges of the sections f' of the opposite sets of ceiling-sections are provided with facing flanges f^{11} , which are staggered in respect to each other in the vertical plane and adapted to under and over lap each other when the parts are in position to close the light-well opening, as shown in Fig. 2. The rearward sections f are never pulled entirely out from under the fixed ceiling at the opposite ends of the light-well. The two or more sections of each set $f f'$ at each side always overlap. Hence in virtue of the lap-joints at the rails the lap-joints between the two sections of the respective sets $f f'$ and the lap-joint formed by the flanges f^{11} when the forward sections meet, as shown in Fig. 2, it is obvious that when the movable ceiling-sections are in position to close the light-well no openings of sufficient size to afford a draft or a ready passage for the flames can exist. Hence when the movable ceilings are in position to close the light-well the fire on any given floor may be much more readily confined thereto than when the light-well remains open. Likewise if the fire is on an upper story the closing of the light-well openings by said movable ceiling will prevent temporarily the streams of water from the hose being poured down through the light-well openings onto the goods in the lower story. Of course it will be understood that the primary purpose is to prevent the spread of the flames. The movable ceilings are not intended to afford a water-tight closure of the light-well opening; but if the fire is on an upper story the closing of the light-well openings on the lower stories by said movable ceilings will temporarily intercept the streams of water which might otherwise be poured through the said openings onto the lower floors.

From the foregoing it will be seen that by my invention I have provided a device which largely lessens the fire-risk on goods in build-

ings having light-well or other openings. By actual usage I have demonstrated the efficiency of this invention and have found that the application thereof to non-fireproof or 5 slow-burning buildings reduces the rate of insurance to a large extent.

It will of course be understood that the movable ceilings will be adapted to the size of the opening which it is desired to close. For some 10 light-wells single sections on opposite sides may be sufficient. In still others one single section might suffice. It will also be understood that the movable ceiling-sections may be made of any suitable material and that the 15 details might be modified without departing from the spirit of my invention.

What I claim, and desire to secure by Letters Patent of the United States, is as follows:

1. In a building, the combination with a 20 fixed ceiling, having a light-well or other opening, of suitably-located sprocket-wheels, a pair of parallel endless chains running over said sprocket-wheels, movable ceiling-sections connected one to the upper and the 25 other to the lower strands of said endless

chains, whereby they will be moved in opposite directions by continuous movements of said chains, and means for simultaneously moving the said sprocket-wheels, substantially as described.

2. The combination with a fixed ceiling having a light-well opening, and a movable ceiling made up of the opposite sets of lap-sections $f'f'$, mounted to move toward and from each other, of the endless chains h mounted 35 to over and under run the said ceiling-sections, and the forward members of the opposite sets of said ceiling-sections, connected to opposite folds of said chains, whereby continuous movement of said chains in opposite 40 directions will cause said sets of ceiling-sections to approach or recede from each other, substantially as described.

In testimony whereof I affix my signature in presence of two witnesses.

MASON H. CRITTENDEN.
